G. T. PARSLEY.

HACK SAW.

APPLICATION FILED JUNE 9, 1921.

Patented Apr. 18, 1922.

UNITED STATES PATENT OFFICE.

GEORGE T. PARSLEY, OF ASHLAND, OREGON.

HACK SAW.

1,413,348.

Specification of Letters Patent. Patented Apr. 18, 1922.

Application filed June 9, 1921. Serial No. 476,217.

To all whom it may concern:

Be it known that I, GEORGE T. PARSLEY, a citizen of the United States, and resident of Ashland, county of Jackson, and State of Oregon, have invented a new and useful Hack Saw, of which the following is a specification.

The present invention relates to improvements in hacksaws and its particular object 10 is to provide a hacksaw in which the blade may be changed with the greatest ease and in which the angle of the blade relative to the frame may be adjusted by merely pressing on a spring, whereby the tension of the 15 blade is released and the same may be rotated in the frame to any desired degree. While in the drawing and in the following description I shall confine myself to the use of the term hacksaw I wish to have it understood that I do not confine myself thereby 20 but wish to secure protection on the general structure, whether used in a hacksaw or in any similar tool used for similar purposes.

I attain my object preferably by means 25 of the mechanism illustrated in the accompanying drawing, in which Figure 1 is a side view of my hacksaw, Figure 2 an enlarged detail view of one of the holders for the blade of the saw, Figure 3 a vertical section through said holder along line 3—3 of Figure 2, Figure 4 an enlarged detail view of the other holder, Figure 5 a vertical section through said other holder along line 5—5 of Figure 4, Figure 6 an enlarged 30 sectional view through the handle of my saw along line 6—6 of Figure 1, Figure 7 an enlarged detail end view of a pawl used for adjusting the tension of the saw, Figure 8 a side view of said pawl and Figure 9 an 35 enlarged detail view of a rack on the handle adapted to be engaged by said pawl.

Referring to the drawing in detail it will be seen that the saw 1 consists of the handle 2, the frame 3 and the blade 6. The frame 45 proper comprises two parts 7 and 8, the former being elbow-shaped and provided with a rack 9 at one end, while the latter is adapted to slidably engage said end and be adjustably secured thereto by means of the 50 pawl 11 engaging the rack 9. The free ends 12 and 14 of the frame are provided with axially alined holes 16 and 17, the former being cylindrical, while the latter is conical, having its larger diameter at the out- 55 side of the frame. In the hole 16 is rota-

tably supported the holder 18 for the saw blade, shown in detail in Figures 2 and 3. It consists of a rod 19 fitting in the hole having a head 21 at the outer end of the hole and an inner end 22 reduced to semi-circular cross-section, from the base of which rises a small stud 23, which is slightly inclined outwardly and is adapted to engage a hole 24 at one end of the blade. This end of the blade is secured in its position by a 60 latch 26 supported in a slot 27 in the holder on the pin 28 and provided with two lateral projections 29 adapted to prevent the holder from slipping out of its hole when the saw 65 blade is removed.

The hole 17 supports a sleeve 31 which forms an integral part of one member of the handle and furnishes a bearing for the second holder 32, which is shown in detail in Figures 4 and 5. This holder is similar to 70 the holder 18 and consists of a rod 33 adapted to rotate in the sleeve 31, having a reduced end 34 with a stud 36 adapted to receive the other end of the blade and a latch 37 to prevent the blade from jumping off 75 the stud. The outer end of this holder is pivotally secured to the elbow of a bell crank lever 38 by the pin 39, the lever being fulcrumed in the yoke 41 on the pin 42. The yoke and the lever form the handle and 80 co-operate with each other in adjusting the tension of the blade. It will be remembered that the yoke is integrally connected with the sleeve 31, which latter, being conical, is firmly braced against the frame. The lever, 85 being fulcrumed in the yoke and having its elbow pivotally connected to the blade, enables the operator to give the blade any desired tension by pressing the long arm 43 of the lever into the yoke as will be readily 90 understood from a glance at the drawing.

The lever can be locked in any desired position by the pawl 44 pivotally secured to its end and engaging the rack 46, the spring 47 holding the pawl in engagement with the 100 rack, while an extension 48 of the pawl provides a convenient means for the operator for liberating the pawl from its engagement.

The use of this saw is very simple. To insert the blade, first adjust the parts 7 and 8 with reference to each other so that the gap between the two holders corresponds somewhat with the length of the blade. Slip one end of the blade under the latch 26 so that its 110

hole 24 registers with the stud 23, then press down on it. Place the hole in the other end of the blade over the stud 36 in the other holder and secure it by the latch 37. A mere 5 pressure on the lever in the handle will then give the blade the proper tension and when the pressure is released, the pawl 44 engages the rack 46 and thereby locks the lever in that position. If it is desired to change the 10 angle of the blade with reference to the saw, the tension of the blade may be released by a slight pressure on the extension 48 of the pawl 44 and the frame may be turned on the two holders as far as is desired.

15 To insure the holder at the far end of the saw against rotation while the saw is being used, I provide small projecting lugs 49 in the frame portion 8 adapted to force themselves into corresponding notches in the head 20 of the said holder.

Various modifications and additions may be made to the device as shown in the drawing without affecting the spirit of the invention.

25 I claim:

1. A saw comprising a frame having two bearings alined with each other, a handle rotating in and supported by one of the bearings, a saw blade supported in the handle and the other bearing so as to be normally rotatable, and means associated with the handle for stretching the blade whereby the handle and the blade are locked against rotation.
- 35 2. A saw comprising a frame having two bearings alined with each other, a handle rotating in and supported by one of the bearings, a saw blade supported in the handle and

the other bearing so as to be normally rotatable, and means associated with the handle 40 for stretching the blade whereby the handle and the blade are locked against rotation, said means comprising a lever fulcrumed in the handle and pivotally engaging the blade for stretching the same.

45 3. A saw comprising a frame having two bearings alined with each other, a handle rotating in and supported by one of the bearings, a saw blade supported in the handle and the other bearing so as to be normally rotatable, and means associated with the handle 50 for stretching the blade whereby the handle and the blade are locked against rotation, said means comprising a lever fulcrumed in the handle and pivotally engaging the end of 55 the blade for stretching the same, a rack in the handle, a pawl pivotally secured in the lever adapted to engage the rack, and means for locking and releasing the pawl.

4. A saw comprising a frame having two 60 bearings alined with each other, a handle rotating in and supported by one of the bearings, a saw blade supported in the handle and the other bearing so as to be normally 65 rotatable, and means associated with the handle for stretching the blade whereby the handle and the blade are locked against rotation, said means comprising a lever fulcrumed in the handle and pivotally engaging the end of the blade for stretching the 70 same, a rack in the handle, a pawl pivotally secured in the lever adapted to engage the rack, a spring adapted to lock the pawl in the rack and manual means for releasing the same.

GEORGE T. PARSLEY.
